AUTOMOBILE GRILLE

George W. Walker, Bloomfield Hills, Mich., assignor to Ford Motor Company, Dearborn, Mich., a corporation of Delaware

Filed Dec. 5, 1960, Ser. No. 63,109

Term of patent 7 years

(Cl. D14—18)

Figures 5, 6, 7, 8 and 9 are enlarged sectional views taken substantially through the lines 5—5, 6—6, 7—7, 8—8 and 9—9, respectively, of Figure 2.

I claim:

The ornamental design for an automobile grille, substantially as shown.
